CLAIM

The ornamental design for a carrying case for portable exhibit display panels or the like, as shown and described.

DESCRIPTION

FIG. 1 is a front perspective view of a carrying case for portable exhibit display panels or the like showing our new design;

FIG. 2 is a rear perspective view thereof;

FIG. 3 is a left side elevational view thereof, the right side being a mirror image;

FIG. 4 is a rear elevational view thereof;

FIG. 5 is a front elevational view thereof;

FIG. 6 is a bottom plan view thereof; and,

FIG. 7 is a top plan view thereof.

FIG. 1**FIG. 2****FIG. 4****FIG. 3****FIG. 5****FIG. 6****FIG. 7**
